UNITED STATES PATENT OFFICE.

DANIEL U. McCORMICK, OF CHICAGO HEIGHTS, ILLINOIS.

WINDOW-SCREEN.

1,099,263.

Specification of Letters Patent.

Patented June 9, 1914.

Application filed April 17, 1913. Serial No. 761,656.

To all whom it may concern:

Be it known that I, DANIEL U. McCORMICK, a citizen of the United States, and a resident of the city of Chicago Heights, 5 county of Cook, and State of Illinois, have invented certain new and useful Improvements in Window-Screens, of which the following is a specification.

My invention relates to improvements in 10 window screens and has for its object the provision of a construction of this character which is strong and rigid and capable of economical manufacture.

The invention consists in the combinations 15 and arrangements of parts hereinafter described and claimed.

The invention will be best understood by reference to the accompanying drawing forming a part of this specification, and in 20 which—

Figure 1 is a face view of a screen embodying my invention, Fig. 2, an enlarged detail view of one of the corners of said screen, Fig. 3, an enlarged section taken on 25 line $x-x$ of Fig. 1, and Fig. 4, an enlarged section taken on line $y-y$ of Fig. 1.

The preferred form of construction as illustrated in the drawing comprises four corner sections 1, 2, 3 and 4, said corner sections 30 being made of sheet metal formed into substantially channel form and telescoping with each other to form an adjustable frame as will be readily understood by those skilled in the art. The inner portion of each of the 35 frame sections is formed into a substantially rectangular channel 5 adapted to receive and retain the wire mesh 6. At its outer side each of said frame members is extended outwardly at 7 and then at right angles to form 40 an upstanding portion 8 having a downwardly turned lip thereon. A retaining member 10 is also formed of sheet metal, stamped into substantially rectangular form in cross section which is adapted to enter 45 channel port 5 to retain the screen mesh 6 therein. This retaining member 10 is provided with an outwardly extending portion 11 at its outer side adapted to be secured to portion 7 by means of a bolt 12 taking 50 through a slot 13 as shown. This arrangement constitutes a simple and effective one for the purpose and admits of some longitudinal movement of the retaining members and the corresponding frame members which 55 facilitates assembling of the parts. The gen-

eral construction is strong and rigid and is capable of economical construction.

While I have illustrated and described the preferred form of construction for carrying my invention into effect, this is capable of 60 variation and modification without departing from the spirit of the invention. I, therefore, do not wish to be limited to the precise details of construction set forth, but desire to avail myself of such variations and 65 modifications as come within the scope of the appended claims.

Having described my invention what I claim as new and desire to secure by Letters 70 Patent is:

1. A screen comprising a frame made up 75 of metallic frame members channel shaped in cross section, the inner portions of said members being formed into channels and the outer portions thereof being extended outwardly from the outer edges of said channels substantially parallel with the general plane of the screen and then extended at substantially right angles to the general plane of the screen and on the open sides of 80 said channels; and retaining members fitting within said channels, substantially as described.

2. A screen comprising a frame made up 85 of metallic frame members channel shaped in cross section, the inner portions of said members being formed into channels and the outer portions thereof being extended outwardly from the outer edges of said channels substantially parallel with the general plane 90 of the screen and then extended at substantially right angles to the general plane of the screen and on the open sides of said channels; retaining members fitting within said channels, the inner portions of said retaining members being formed into channels fitting the channels in said frame members and the outer portions of said retaining members being extended outwardly to fit the outwardly extending portions of said frame 95 members, substantially as described.

3. A screen comprising a frame made up 105 of metallic frame members channel shaped in cross section, the outer portions of said members being extended outwardly and then at substantially right angles to the plane of the screen and the inner portions thereof being formed into substantially rectangular channels; and retaining members channel shaped in cross section and fitting within 110

said rectangular channels to secure the screen mesh therein, the outer portions of said retaining members being secured to the outwardly extending portions of said frame members, substantially as described.

4. A screen comprising a frame made up of metallic frame members channel shaped in cross section, the outer portions of said members being extended outwardly and then at substantially right angles to the plane of the screen and the inner portions thereof being formed into substantially rectangular channels; and retaining members channel shaped in cross section and fitting within said rec-

tangular channels to secure the screen mesh 15 therein, the outer portions of said retaining members being secured to the outwardly extending portions of said frame members by a bolt-and-slot connection, substantially as described.

In testimony whereof I have signed my name to this specification in the presence of two subscribing witnesses.

DANIEL U. McCORMICK.
